ABSTRACT: Method and apparatus to continuously detect and measure the moisture level and/or temperature of a moving web of material. The web of material is run between a pair of vibrating members which rapidly move air back and forth through the web of material to bring the moisture content of the air into equilibrium with the moisture content of the fabric.

MOISTURE AND TEMPERATURE DETECTION

In the processing of certain sheets of material such as paper, textile fabrics, etc., it is necessary or desirable to measure the temperature and/or moisture content of the sheet during processing. This is especially true when one of the process steps is drying wherein you want to maintain a certain moisture level in the product being processed since a moisture content above or below a certain level indicates that the material is being under or over dried. This is particularly true in the processing of textile fabrics. Preferably, such measurement of moisture content and/or temperature should be continuous so that an operator can continuously check and readjust the processing equipment to maintain substantially uniform conditions. Preferably, the desired uniform conditions should be the relative humidity and/or temperature of the area wherein the web material is to be further processed.

The percent moisture content of a given piece of textile material is determined primarily by the relative humidity of its environmental air and secondarily by its environmental temperature. It is customary to speak of the moisture content as being that moisture content which is present under standard environmental conditions such as 70° F. and 65 percent relative humidity.

Moreover, a plot or graph, such as that shown in FIG. 3, may be made of the moisture present in fabric or fibers under any specified conditions such as 40 percent, 50 percent or 60 percent relative humidity. When such determinations have been made, such data may be plotted so that if a piece of fabric has been conditioned (i.e., allowed to come into equilibrium with its environmental surroundings), its moisture content may be derived from the graph by knowing the conditions of the environment, providing that sufficient time has elapsed for the material to come into equilibrium.

In web drying operations, generally speaking it is desired to bring the web out of the dryer at a moisture content such that the web neither gains nor loses moisture when brought into the surrounding conditions of relative humidity in the room. To dry more than this is a waste of heat and to dry less than this is to run the risk of mildew.

Normally, in conditioning fabric for test, the fabric is suspended to permit free air flow around the fabric in a room which is controlled as to relative humidity and temperature. This means that the fabric absorbs or loses moisture to bring it to equilibrium because of the unlimited air flow available. Now if we surround the fabric with only a small amount of air then the air will gain or lose moisture from or to the fabric, or we will be conditioning the air to the fabric. Since the absolute weight of moisture present in the air is small in comparison with that in the fabric then this is accomplished with little change in the fabric moisture.

Therefore, it is an object of the invention to accurately measure the moisture content of a continuously moving web of material.

Other objects and advantages will be clearly apparent as the specification proceeds to describe the invention with reference to the accompanying drawing in which:

FIG. 1 is a schematic representation of the new and novel moisture detector;

FIG. 2 is a blowup cross-sectional view of the moisture detector per se; and

FIG. 3 shows a typical fabric moisture graph.

In the continuous processing of sheet material, it is usually necessary to measure the moisture level in the material to ascertain whether certain process steps are being properly controlled. In the preferred form of the invention shown in FIGS. 1 and 2, textile fabric 10 is being dried in dryer 12 and is taken up on a takeup roll 14. As discussed briefly before, the invention is not restricted to textile fabric but can be employed on such material as paper or on individual strand material such as warp yarn from a warp beam. To accomplish the moisture detection, a moisture detector, generally designated 16, is located between the dryer 12 and the takeup 75

roll 14 with the fabric 10 passing between two opposed loud speakers 18 and 20 mounted on baffle plates 22 and 24, respectively.

The moisture present in a piece of material will come into equilibrium with its environment, which is to say that a piece of fabric conditioned under certain conditions and held in an area with a certain temperature and humidity, will come into equilibrium with the surrounding air and the air will come into equilibrium with the fabric. Logically, it follows that the equilibrium condition can be reached much faster if the surrounding air is moved back and forth through the fabric. The air, under such condition, rapidly picks up moisture from the fabric until it is in equilibrium therewith.

To accomplish the above result, the diaphragms 26 and 28 are connected to a power source P to induce reciprocal movement of the movable coils 30 and 32 to cause the diaphragms 26 and 28 to be vibrated out of phase with one another to pump the air back and forth through the fabric 10, which pumping action rapidly brings the air and the fabric into equilibrium. Mounted on one or the other of the loud speakers 18 or 20 is a hygroscopic transducer 34 which in response to the amount of moisture in the air changes the electrical resistance in the circuit of the meter 36 which is calibrated to read directly in percent relative humidity.

The relative humidity reading can be used in many ways. Obviously, this reading can be employed to merely check on the condition of the fabric at any desired time. Also, it can be employed to control the rate of drying of the drier in order to maintain certain preselected conditions. In processing a fabric, the fabric, after drying, can be either processed further or placed in storage. These further steps will take place in areas having a certain relative humidity and temperature. If the measured relative humidity or temperature is below the relative humidity of the area in which the further steps are taken then the drier is taking too much moisture out of the fabric since the fabric when processed further will pick up moisture and come into equilibrium with the surrounding atmosphere of the other area.

The preferred embodiment is directed to obtaining relative humidity measurements but obviously temperature measurements of the air can be also taken in the same manner if it is desired to measure temperature.

The specific preferred detector 16 consists of the baffle plates 22 and 24, which are approximately 3 feet square and mounted one-half inch apart, and the loud speakers 18 and 20, mounted to the baffles by such means as screws 19, which have a frequency of vibration of the order of 60 times per second. The loud speakers 18 and 20 are of the conventional commercially available type which have a movable coil 30 or 32 attached to a diaphragm 26 or 28, a field magnet 38 or 40, a magnetic field winding 42 or 44 and a core 46 or 48.

The herein disclosed detector and method of use provides for rapid and continuous measurement of a moving strand or strands of yarn and continuous lengths of material being processed. The close spacing of the baffles 22 and 24 and the vibration frequency of the diaphragm allows the pumped air to come to equilibrium with the fabric very quickly since only a small amount of moisture from the fabric is necessary.

Although I have described in detail the preferred embodiment of the invention, it is contemplated that many changes may be made without departing from the scope or spirit of the invention and I desire to be limited only by the claims.

That which I claim is:

1. A method of measuring a condition of a moving length of material comprising the steps of: providing a moving length of material, moving a small amount of gaseous fluid back and forth through said length of material to bring said gaseous fluid in equilibrium with said material and sensing and measuring a physical property of the gaseous fluid.

2. The method of claim 1 wherein said gaseous fluid is air.

3. The method of claim 2 wherein said air is pumped back and forth through said fabric.

4. A method of measuring the moisture content of a moving length of material comprising the steps of: providing a moving length of material, moving a small amount of gaseous fluid back and forth through said length of material to bring said gaseous fluid in equilibrium with said material, sensing the moisture content of said gaseous fluid and measuring the humidity of the sensed moisture content.

5. The method of claim 4 wherein said gaseous fluid is air.

6. The method of claim 5 wherein said air is pumped back and forth through said fabric.

7. A detector to measure a physical property of a length of material comprising: a pair of plates spaced from one another, a first opening in one of said plates, a second opening in the

other of said plates opposite to said first opening, means to pump air operably associated with said plates to pump air back and forth through said openings and a sensing means in the path of travel of said air.

5 8. The structure of claim 3 wherein said pumping means includes a first vibrating diaphragm over said first opening and a second vibrating diaphragm over said second opening.

9. The structure of claim 3 wherein means are provided to vibrate said diaphragm out of phase with one another.

10 10. The structure of claim 5 wherein said sensing means includes a hygroscopic transducer.

UNITED STATES PATENT OFFICE
CERTIFICATE OF CORRECTION

Patent No. 3,595,070 Dated July 27, 1971

Inventor(s) Philip N. Smith

It is certified that error appears in the above-identified patent and that said Letters Patent are hereby corrected as shown below:

Column 4, line 5, "claim 3" should read -- claim 7 --; line 8, "claim 3" should read -- claim 8 --; line 9, "diaphragm" should read -- diaphragms --; line 10, "claim 5" should read -- claim 9 --.

Signed and sealed this 29th day of February 1972.
